UNITED STATES PATENT OFFICE.

CARLO COLEATTI, OF MILAN, ITALY.

FIRE GRATE.

Application filed October 20, 1920. Serial No. 418,925.

To all whom it may concern:

Be it known that I, CARLO COLEATTI, a subject of the King of Italy, residing at Milan, in the Kingdom of Italy, have invented certain new and useful Improvements in and Relating to Fire Grates, of which the following is the specification.

This invention relates to improvements in the fire grate disclosed in my prior application for patent filed October 28, 1919, Serial No. 333,969, and has for its object to provide a special form of grate bar having a trapezoidal cross-section for the purpose of securing a more efficient draft in a furnace and for obtaining a durable and simple connection of the bars with frame and grate.

With the foregoing objects outlined and with other objects in view which will appear as the description proceeds, the invention consists in the novel features hereinafter described in detail, illustrated in the accompanying drawing and more particularly pointed out in the appended claims.

Referring to the drawing:

Figure 1 is a plan view of three of my improved bars in assembled relation.

Fig. 2 is a front view of the same.

Fig. 3 is an end view of one of the bars.

Fig. 4 is a horizontal sectional view taken on line 4—4 of Fig. 2.

Fig. 5 is a vertical sectional view of one of the grate bars taken on line 5—5 of Fig. 1.

Fig. 6 is a rear view of one end portion of one of the grate bars.

In the drawing, 2 designates the grate bars, each of which in the present instance is of substantially V-shape in plan and is provided at its ends with outwardly extending lugs 3 designed to rest on a grate frame (not shown). The lugs are provided on the undersides with recesses 3" into which the upper edges of said frame may

project. Each end of each of the grate bars is also provided with an outwardly extending lug 2, which as shown in Fig. 3 is arranged mainly below the lug 3. The ends of each bar are also provided with forwardly extending thin lugs *t* having a horizontally disposed upper edge *t'*, a vertical edge *t²* and an inclined edge *t³*.

In assembling the grate bars on a grate frame, the lugs 3 will rest on the upper edge of the frame and the lugs 2 will interlock with the lugs *t* as shown in Figure

4. As shown in this figure the inner surface *z'* of one lug 2 will lie adjacent to the outer surface *z²* of an adjacent lug *t*. Further, the upper edges *t'* of the lugs *t* will support the lower edges *a'* of small lugs *a²*. The edge *a'* is in substantial alignment with the upper edge of the lug *z*, so, as shown in Figure 3, one line suffices to show practically both edges. The lugs *a²* and *z* are offset relatively to one another as shown in Figure 6.

Owing to this construction the grate bars will be interlocked together, and an intermediate grate bar can only be removed by taking out all of the grate bars in front of the same.

As best shown in Figure 5, each bar is of trapezoidal cross-section.

The central portion of each bar is provided with a wedge shaped lug 8 and a corresponding groove 8'. Each of the lugs 8 tapers towards its lower end, as shown in Fig. 2 so that it cooperates with the groove 8' of an adjacent bar to direct air passing through the grate outwardly or away from the longitudinal center of the grate as shown by the arrows *y* in Figure 1.

Further, the front face of each grate bar is provided near its upper end with inwardly extending surfaces 3' which function to direct air passing through the grate towards the longitudinal center of the grate as shown by the arrows *x*.

From the foregoing, it is believed that the construction, operation and arrangement of parts may be readily understood by those skilled in the art, and it is apparent that changes may be made in the details disclosed without departing from the spirit of the invention as expressed in the claims.

Having now particularly described the nature of my invention and the way in which the same should be performed, I claim:

1. In a grate, a fire bar of substantially V-shape in plan, the opposite legs of said bar being inclined upwardly from the lower to the upper edge of the bar and being of trapezoidal cross-section, means at the outer ends of said legs for interlocking the bar with adjacent bars, and surfaces provided at the outer ends of said legs for directing air currents toward the central portion of the bar.

2. A grate of the kind defined by claim 1 in which the central portion of the bar is

provided on one side with a groove and on its opposite side with a projecting rib, said groove being adapted to cooperate with the rib of an adjacent section to guide air passing through the grate, and the first mentioned rib being adapted to cooperate with the groove of an adjacent bar to guide air passing through the grate.

3. A grate, including a series of fire bars arranged side by side, each fire bar being of substantially V-shape in plan and having a central portion and angularly arranged oppositely extending legs, said legs being inclined upwardly from the lower to the up-

per edge of the bar and each leg having 15 a trapezoidal cross-section, surfaces provided at the outer ends of said legs for directing air passing between the bars toward the central portions of the bars, lugs and recesses provided at the outer ends 20 of each bar adapted to interfit with similar lugs and recesses in adjacent bars, and certain of said lugs being provided with grooves adapted to receive the side bars of a supporting element.

In witness whereof I affix my signature.

CARLO COLEATTI.
